HUGO KURTZNER, OF CLEVELAND, OHIO, ASSIGNOR TO THE KURTZNER RADIATOR COMPANY, OF CLEVELAND, OHIO, A CORPORATION OF OHIO.

RADIATOR-SECTION.

1,086,061.

Specification of Letters Patent.

Patented Feb. 3, 1914.

Application filed September 2, 1911. Serial No. 647,354.

To all whom it may concern:

Be it known that I, HUGO KURTZNER, a citizen of the United States, residing at Cleveland, in the county of Cuyahoga and State of Ohio, have invented a certain new and useful Improvement in Radiator-Sections, of which the following is a full, clear, and exact description.

This invention relates to radiator sections of a construction particularly applicable to use on automobiles, but it is not intended to confine it to this particular service for it may be useful in many other lines where thermal changes in one fluid are to be effected by means of another fluid separated from the first by thin sheet-metal walls so constructed as to offer the maximum of surface in minimum space and with minimum weight. In order to keep down the weight these separating walls are preferably made of very thin and light sheet metal that has not sufficient rigidity, in flat form of any considerable area to withstand the strains and duty called for this service. In order, therefore, to adapt them to the work, the sheet-metal plates of which the radiator is composed are formed in such manner as to impart to them strength and rigidity and also adapt them to being assembled in compact order, and when so assembled to strongly reinforce and support each other. To effect these ends and also to increase the area of radiating surface within a given space, each plate is formed with a series of transverse, connected corrugations, the main or central portion of each corrugation being semi-cylindrical, a shape having the greatest strength for a given amount of metal. The ends of the corrugations are made slightly larger than the central portions and formed with multiple flat sides, these end enlargements practically forming continuous shoulders along the edges of the plate, and when assembled lying in surface contact with and lending support to the shoulders of the next adjacent plates. In order to further strengthen and support the cylindrical portions of the corrugations between their end shoulders each has formed in it one or more intermediate transverse enlargements or grooves which project as ribs beyond the plane of the outer surface of the corrugation. The plates thus formed are assembled symmetrically in pairs, face to face, so that

the concavities of the corrugations match and form substantially cylindrical air passages or tubes through the pair; and the pairs are then assembled back to back to form vertically disposed water passages between the convex faces of adjacent pairs, the cylindrical portions of the corrugations being held apart, for the purpose of forming these passages, by means of the enlarged end shoulders and the intermediate ribs which lie in contact with the corresponding shoulders and ribs of the next adjacent plates.

The pairs of plates are, preferably, assembled unsymmetrically, so that the tubes are staggered as between adjacent pairs, and the vertically disposed water passages formed between them is thus made tortuous and of expanding and contracting widths, so that the flow of water through them is turbulent and changing. When the plates are assembled as described their edges are dipped into molten solder which firmly unites them and seals the edges of the vertical water passages.

In Patent No. 943,257, granted December 14, 1909, to the same inventor, is shown a radiator section having cylindrical corrugations or tubes similar in construction and assembled disposition to those of this present invention, which is merely an improvement on said prior device. In the device of that patent the enlarged shoulders at the ends of the tubes are, like the tubes, cylindrical in form, and when assembled they merely touch the shoulders of adjacent plates at their minute meeting points. This results in the formation of open spaces of considerable extent between the outer sides of the shoulders which spaces must be filled and tightly sealed by the solder which binds the plates together. It requires a large amount of solder to fill these spaces, thereby materially increasing the weight of the sections and also the manufacturing cost, for the solder is expensive. It also detracts somewhat from the strength of the structure owing to the use of large masses of solder, which is soft in its nature, to span the spaces and join the harder sheet metal of the plates. These features are purely structural and are by no means considered as defects or as in any manner adversely affecting the operation of the prior radiator, and

they are pointed out merely to make clearer, by comparison, the advantages of this present invention.

In the accompanying drawing, which shows a preferred construction of the present invention, together with some modifications thereof, Figure 1 is an inside face elevation of a portion of one of the formed plates used in the construction of a radiator section; the left hand end showing an enlargement or shoulder having multiple flat sides arranged in semi-hexagon order while the enlarged shoulder at the right hand end has its multiple flat sides arranged in semi-square order. Figs. 2 and 3 are end elevations of the left and right hand edges respectively of the plate of Fig. 1. Fig. 4 is a front elevation of portions of an assembled group of plates having the hexagon form of enlarged end shoulders, the bare edges of some of the plates being shown, while others are covered by the solder (shown by dots) which is used to bind the plates together and to tightly seal the edges of the vertical water spaces. Fig. 5 is a similar view of portions of an assembled group of plates having square end shoulders. Fig. 6 is a vertical transverse section through the tubular portions of a group of plates the section being taken on the line 6, 6 of Fig. 1. Fig. 7 is a similar section through the intermediate enlargements or contact ribs of the tubes, the section being on the line 7, 7 of Fig. 1. Fig. 8 is a modification showing multiple sided end shoulders arranged in rectangular order, thereby admitting of a wider spacing of the tubes and increased widths of the vertical water passages.

The sheet-metal plates are formed with transverse semi-cylindrical corrugations or half tubes, which at their ends are enlarged to form shoulders 2 or 3, having multiple sides of such geometrical dispositions as will admit of their lying, when assembled, back to back in close surface contact with the sides of corresponding shoulders on the next adjacent plates, leaving practically no intervening open spaces between them and having a double thickness of the sheet metal entirely around each completed end opening of the tubes as shown in Figs. 4 to 8. These enlargements practically form continuous shoulders along the edges of each plate.

Each corrugation forms one half of a complete cylindrical air tube and each end shoulder one half of the proposed geometrical outline of the end opening. Each plate is so formed that the edges of its corrugations are connected longitudinally by slight bends 4 while its end shoulders are similarly connected by bends 5 which double back the wall sections 6 of two adjacent shoulders thereby forming a double thickness of metal in these intermediate sides, such sides, in a single plate, being only half the length of

the full side of the completed geometrical figure formed by a pair of plates symmetrically assembled face to face and in contact along the convexities 4 and 5.

The corrugations are formed with one or more intermediate enlargements or ribs 9, which project above the plane of the convex outer sides of the corrugations and, when assembled, contact with similar ribs on the next adjacent plates, whereby the tubes are supported one by another on lines of support extending through the center of the radiator.

The pairs of plates are preferably assembled unsymmetrically, back to back, the tubes of adjacent pairs being staggered and the vertically disposed water passages between them thus made tortuous, and of alternately expanding and contracting widths, as at 7 and 8 respectively. The convexed back sides of the tubes are held out of contact to form these water passages by means of the enlarged shoulders 2, 3 or 10 at their ends and the intermediate ribs 7 which contact with similar shoulders and ribs of the adjacent plates.

The enlarged end shoulders of the tubes are formed with multiple flat sides so geometrically disposed that when assembled the shoulders will lie in flat surface contact on every side with the shoulders of adjacent plates and with practically no intervening open spaces between adjacent shoulders. In consequence of this there is a double thickness of sheet metal around every side of every opening in the faces of the radiator, and the sheet metal of the plates extends to these faces and completely fills the entire space on each face except that which is left open for the air passage.

In order to have the flat sides of the shoulders meet in surface contact on every side with similar sides of other shoulders the sides must be disposed in such geometrical order as will admit of their being grouped or assembled in this manner. For this purpose the hexagon formation 2, shown at the left end of Fig. 1 and in Figs. 2, 4, 5, 6 and 7, is considered preferable, but they may be made in square forms 3 as shown at the right end of Fig. 1 and by Figs. 3 and 5, or even rectangular as shown at 10 in Fig. 8.

If desired the shoulders of the tubes may be of the same formation at both ends or they may be differently shaped at opposite ends as shown in Fig. 1. This having differently shaped openings on opposite faces of the radiator is advantageous, in trade, in that the two forms to be conspicuously displayed in front, as in an automobile radiator.

The rectangular formation 9 of Fig. 8 permits of greater spacing between the outside of the tubes and consequently greater width of the vertical water passages.

Having thus described the invention what is claimed as new and useful is:

1. A section for radiators composed of a number of independently formed sheet-metal plates each of which extends from the top to the bottom of the radiator section and is formed with transverse semi-cylindrical corrugations which have slight enlargements at their ends that are formed with multiple flat sides and constitute continuous shoulders along the edges of the plate, said plates being symmetrically assembled in pairs, face to face, so as to form substantially cylindrical horizontal air passages through the radiator, and the pairs being unsymmetrically assembled so as to form tortuous vertically disposed water passages of expanding and contracting widths between the convex outer surfaces of the plates which are held apart for the formation of these water passages by means of said enlarged shoulders and the intermittent enlargements of the corrugations which contact with corresponding shoulders and enlargements on the next adjacent plates, said shoulders having such regular geometrical formation that their outer flat sides will lie in surface contact with the flat sides of the shoulders on the next adjacent plates with practically no intervening open spaces between them, the edges of the shoulders and hence also the plates being bound together by solder. 70 75 80 85 90 95 100 105 110 115 120 125 130
2. A section for radiators composed of a number of independently formed sheet-metal plates each of which is transversely corrugated the corrugations having slight enlargements at their ends which enlargements form continuous shoulders along the edges of the plate and transverse enlargements of the corrugations intermediate their ends, said plates being assembled in pairs face to face to form horizontally disposed air passages through the radiator and the pairs being assembled back to back form vertically disposed water passages between the outer surfaces of the plates which are held apart for the formation of these water passages by means of said enlarged shoulders and intermediate enlargements of the corrugations which contact with corresponding shoulders and enlargements of the next adjacent plates, the edges of the shoulders and hence the plates being bound together by solder. 40 45 50 55 60 65 70 75 80 85 90 95 100 105 110 115 120 125 130
3. A section for radiators composed of a number of independently formed sheet-metal plates each of which extends from the top to the bottom of the radiator section and is formed with transverse semi-cylindrical corrugations which have slight enlargements at their ends that are formed with multiple flat sides and constitute continuous shoulders along the edges of the plate the corrugations having also transverse enlargements intermediate their ends, said plates being symmetrically assembled in pairs, face to face, so as to form substantially cylindrical air passages through the radiator and the pairs being unsymmetrically assembled so as to form tortuous, vertically disposed water passages of expanding and contracting widths between the convex outer surfaces of the plates which are held apart for the formation of these water passages by means of said enlarged shoulders and the intermittent enlargements of the corrugations which contact with corresponding shoulders and enlargements on the next adjacent plates, said shoulders having such regular geometrical formation that their outer flat sides will lie in surface contact with the flat sides of the shoulders on the next adjacent plates with practically no intervening open spaces between them, the edges of the shoulders and hence also the plates being bound together by solder. 5 10 15 20 25 30 35 40 45 50 55 60 65 70 75 80 85 90 95 100 105 110 115 120 125 130
4. A radiator section composed of a plurality of independently formed thin metal plates, each of which is formed with transverse concavo-convex corrugations which are all faced in the same direction and are serially united by integral sharply bent-back parts of the metal, all of said corrugations being slightly enlarged at both ends to form continuous shoulders along both edges of the plate, each of said enlargements forming one-half of a regular flat-sided geometrical figure, and each of said one-half figures having as each of its end members a part which forms one-half of one side of the whole geometrical figure, and each of said half-side end members being integrally connected with the corresponding part of the enlarged shoulder of adjacent corrugations by a sharply bent back part of the metal, such plates being arranged substantially as shown to face alternately in opposite direction, the two adjacent plates which face one another being arranged so that the sharply bent back connections between adjacent corrugations on said plates will be aligned and will be in substantial contact, and adjacent plates which lie back to back being arranged so that said sharply bent back connecting parts of the metal will be in staggered relation, and so that the outer surfaces of the complete flat sides of the several enlargements or shoulders shall be in full surface contact with the flat sides of the enlargements or shoulders of the adjacent plate which is backed up against it, and the edges of the shoulders, and hence also of the plates, being bound together by solder. 85 90 95 100 105 110 115 120 125 130
5. A radiator section composed of a plurality of independently formed thin metal plates, each of which is formed with transverse concavo-convex corrugations which are all faced in the same direction and are serially united by integral sharply bent-back parts of the metal, all of said corrugations being slightly enlarged at both ends to form continuous shoulders along both edges of the plate. 125 130

- the plate, each of said enlargements forming one-half of a regular flat-sided geometrical figure, and each of said one-half figures having as each of its end members
- 5 a part which forms one-half of one side of the whole geometrical figure, and each of said half-side end members being integrally connected with the corresponding part of the enlarged shoulder of adjacent corrugations by a sharply bent back part of the metal,—said plates being arranged substantially as shown so that the corrugations on alternate plates face in opposite directions, and so that the contiguous plates which lie
- 10 15 back to back have their corrugations set in staggered relation and the flat sides of their enlarged shoulders in substantially complete surface contact with practically no intervening space between them, and so that the adjacent plates which face one another are arranged with the bent back metal connections between corrugations in alignment and in substantial contact,—the edges of the shoulders and hence of the plates being connected by solder.
- 20 25 30 35 40 6. A section for radiators composed of a number of independently formed sheet-metal plates each of which is transversely corrugated, the corrugations having slight enlargements at their ends, which enlargements form continuous shoulders along the edges of the plates, said plates being assembled in pairs face to face to form horizontally disposed air passages through the radiator and the pairs being assembled back to back to form vertically disposed water passages between the outer surfaces of the plates which are held apart for the formation of these water passages by means of said enlarged shoulders of the corrugations
- which contact with corresponding shoulders on the next adjacent plates, the edges of the shoulders and hence the plates being bound together by solder.
7. A section for radiators composed of a 45 number of independently formed sheet-metal plates, each of which extends from the top to the bottom of the radiator section and is formed with transverse semi-cylindrical corrugations which have slight 50 enlargements at their ends that are formed with multiple flat sides and constitute continuous shoulders along the edges of the plate, said plates being symmetrically assembled in pairs, face to face, so as to 55 form substantially cylindrical air passages through the radiator and the pairs being unsymmetrically assembled so as to form tortuous, vertically disposed water passages of expanding and contracting widths between 60 the convex outer surfaces of the plates which are held apart for the formation of these water passages by means of said enlarged shoulders of the corrugations which contact with corresponding shoulders on the next 65 adjacent plates, said shoulders having such regular geometrical formation that their outer flat sides will lie in surface contact with the flat sides of the shoulders on the next adjacent plates with practically no intervening open spaces between them, the edges of the shoulders and hence also the plates being bound together by solder.
- In testimony whereof, I hereunto affix my signature in the presence of two witnesses. 75
